United States Patent Office

Des. 230,456
Patented Feb. 26, 1974

230,456

FLOOR MAT OR THE LIKE

Henry L. White, 24 Livingston St.,
Lincoln, R.I. 02865

Filed Dec. 29, 1971, Ser. No. 213,800

Term of patent 7 years

Int. Cl. D6—11

U.S. Cl. D6—212

FIG. 1

FIG. II

FIG. 1 is a top plan view of the ornamental features of my design, the configuration shown broken away being continuous throughout; and

FIG. 2 is a cross-sectional view taken substantially along the lines II-II of FIG. 1.

I claim:

The ornamental design for a floor mat or the like, substantially as shown.
